UNITED STATES PATENT OFFICE.

JOHN B. BASKERVILLE, OF ROANOKE, VIRGINIA.

VERIFIER.

1,370,267.

Specification of Letters Patent.

Patented Mar. 1, 1921.

Application filed June 29, 1920. Serial No. 392,781.

To all whom it may concern:

Be it known that I, JOHN B. BASKERVILLE, a citizen of the United States, residing at Roanoke, in the county of Roanoke and 5 State of Virginia, have invented certain new and useful Improvements in Verifiers, of which the following is a specification.

This invention relates to verifiers and more particularly to verifiers for verifying 10 the loading of freight.

It is the practice of many of the railroads to use what is known as the affirmative loading system in the loading of freight, which system consists in the loading clerk using a 15 loading ticket on which he places a distinctive designation, such, for instance, as a number, which loading ticket with the number thereon, he gives to the trucker, directing the trucker to place such articles of 20 freight which he has loaded on his truck in a certain designated car, there having been placed in such designated car at a convenient point for use, a rubber stamp and ink pad, the rubber stamp bearing a number 25 corresponding to the number which the loading clerk has placed on the loading ticket. The trucker after discharging the articles of freight from his truck in the car, stamps the loading ticket with the rubber stamp placed therein, and returns the 30 stamped ticket to the loading clerk, who can, at a glance, tell whether the freight has been loaded in the proper car, and thus avoid erroneous shipments. If the trucker 35 loads the articles of freight from his truck in a car other than the one designated by the loading clerk, and uses the stamp placed in such car, which stamp has a different designation or number than the designation 40 or number placed by the loading clerk on the loading ticket, and the loading clerk does not detect the discrepancy between the number which he has placed on the loading ticket and the number which the trucker 45 has stamped on the ticket, when the trucker returns the ticket to him, and the freight is reported short from the point to which it

was intended to be shipped, it can be readily traced by referring to the loading ticket, which will show what car the freight was 50 placed in, then referring to the car record for that day, which will show just where the car containing the freight which was erroneously loaded therein, went to. For a detailed description of my invention, reference may be had to the accompanying drawing, and the reference characters thereon, 55 which form a part of this specification.

The drawing shows a perspective view of my invention. Reference number 1 indicates a base plate with an aperture 2 through the upper end thereof, for hanging the device upon a nail or peg. 3 represents an inking pad carried by the base plate 1. 4 is an oscillating table hingedly related to 60 base plate 1 as at 5. 6 are rubber type which are adapted to be brought into contact with inking pad 3, when the oscillating table 4 is moved upwardly, whereupon the type 6 are inked when the table is permitted 65 to return to its normal position by gravity when the loading ticket is pressed against the face of the type, thereby making an impression of the type carried by the oscillating plate 5 on the loading ticket. 70

Having thus described my invention what I claim is—

1. In a verifier, a fixed upright member, a movable member normally lying at right angles to the fixed member and adapted to 80 be moved into contact and lie parallel therewith, an inking element carried by one of said members, and type carried by the other of said members.

2. In a verifier, a base plate, a movable 85 member normally lying at right angles and pivotally related thereto and adapted to be moved into parallel relation therewith, an inking element carried by said plate and type interposed between said element and 90 said member.

In testimony whereof I affix my signature

JOHN B. BASKERVILLE.
